DESCRIPTION

U.S. PATENT DOCUMENTS

FIG. 1 is a top front perspective view of a wall-mounting television prop for DLP showing our new design;

D484,332 S * 12/2003 Niitsu D6/474
D508,171 S * 8/2005 Choo D6/474
D537,656 S * 3/2007 Stenhouse et al. D6/474
D545,604 S * 7/2007 Eyman et al. D6/574
D546,103 S * 7/2007 Eyman et al. D6/574

FIG. 2 is a front elevational view thereof;

FIG. 3 is a rear elevational view thereof;

FIG. 4 is a left side elevational view, the right side being symmetrical thereof;

FIG. 5 is a top plan view thereof; and,

FIG. 6 is a bottom plan view thereof.
